US00D981511S

(12) **United States Design Patent** (10) Patent No.: **US D981,511 S**
(45) Date of Patent: ** *Mar. 21, 2023

(54) **ROWING MACHINE**(71) Applicant: **Hydrow, Inc.**, Cambridge, MA (US)(72) Inventors: **Taehak Kwon**, Brookline, MA (US);
Julianna Miller, Boston, MA (US)(73) Assignee: **Hydrow, Inc.**, Cambridge, MA (US)

(*) Notice: This patent is subject to a terminal disclaimer.

(**) Term: **15 Years**(21) Appl. No.: **29/835,628**(22) Filed: **Apr. 20, 2022****Related U.S. Application Data**

(63) Continuation of application No. 29/750,571, filed on Sep. 15, 2020, which is a continuation of application No. 29/656,695, filed on Jul. 16, 2018, now Pat. No. Des. 898,843.

(57)

CLAIM

The ornamental design for a rowing machine, as shown and described.

DESCRIPTION

FIG. 1 is a front perspective view of our rowing machine.

FIG. 2 is a right side view of FIG. 1.

FIG. 3 is a left side view of FIG. 1; and,

FIG. 4 is a back perspective view of FIG. 1.

The broken lines illustrate environmental features that form no part of the claimed design. The bottom surface of the rowing machine forms no part of the claimed design. Claimed surfaces are illustrated with shading lines.
